ELECTRICITY-CONTROLLED MUSICAL INSTRUMENT

Oskar Vierling, Berlin, Germany, assignor to
Miessner Inventions, Inc., a corporation of
New Jersey

Original application October 29, 1931, Serial No.
571,824. Divided and this application May 12,
1933, Serial No. 670,761. In Germany Novem-
ber 3, 1930

14 Claims. (Cl. 84—1)

My invention relates to electricity-controlled musical instruments and more particularly to instruments of the kind in which a mechanically actuated oscillator or tuned vibrator, such as for instance a string, influences by induction an electric circuit so that alternating currents of a frequency corresponding to the frequency of the oscillator are produced in the circuit, the current being fed, directly or indirectly, to a loudspeaker or the like. This application is a division of my co-pending application, Serial Number 571,824, filed October 29, 1931, now Patent No. 1,933,299, granted October 31, 1933.

In instruments of the type described it is frequently desirable to reduce the momentary high amplitude of the tone at its inception, and the amplitude of incidental sounds accompanying the tone inception. In the case of a string percussively excited such incidental sounds may comprise the sound of the hammer touching or hitting the string; and such sounds are hereinafter generally referred to as touch noise. It is an object of my invention to provide means for reducing the touch noise and the tendency of the tone intensity to decrease rapidly after the touch. According to my invention this is accomplished by arranging or shaping the parts of the electric circuits influenced by the mechanical oscillators in such manner that the initial oscillations of the oscillator are not or are poorly reproduced by the electric circuit.

Other objects and advantages of my invention will become apparent from the following description in connection with the accompanying drawing. In the latter

Fig. 1 is a schematic diagram of one embodiment of my invention as applied to a single string;

Figs. 2 and 3 are curves illustrating the principle of operation of my invention;

Fig. 4 is a schematic diagram of another embodiment of my invention as applied to a group of strings such as those of a piano; and

Fig. 5 is a perspective and schematic diagram of a still further embodiment of my invention as applied to a single string.

Referring now to the drawing and first to Fig. 1, 1 is the cross section of the string of an instrument, for instance a piano or a violin, which is actuated for example by a hammer 1h adapted to strike the string and to excite initial vibration thereof in the plane indicated by A—B. 18 is a magnet having pole 19 arranged normal to the plane A—B, and carrying winding 21. This winding is connected to the input terminals 4

of an electron discharge tube 5 having a cathode 6, a grid 7 and an anode 8. The cathode is energized by any suitable and well-known means (not shown). The anode circuit contains in series a loudspeaker 9 and the battery B.

When the string 1 is struck by the hammer 1h it will oscillate initially in the plane A—B with relatively large amplitude. After some time, however, the string will not oscillate any more in the plane A—B, but in such manner that the section of the string shown in the figure describes a curve, for instance an ellipse E, or a circle or the like, but even the position of this ellipse may not be fixed unless means, described hereinafter, are provided for this purpose.

Now obviously the oscillating string will induce in the winding 21 an alternating current of a frequency corresponding to the oscillating frequency of the string. This current is amplified by the tube 5 and fed to the loudspeaker 9, which of course produces a sound or tone corresponding to the current. A typical current wave as induced in winding 21 is shown in Fig. 2. A current is merely induced by that component of the string oscillation which is normal to the pole piece 19 of the magnet 18. Therefore the current induced in the winding 21 has its maximum at the beginning of the oscillation of the string 1, when the string oscillates with a relatively large amplitude in the plane A—B. When the oscillations of the string change over to the elliptical form the effective component of the string oscillations rapidly decreases, so that a current wave as shown by the curve i in Figure 2 is obtained. a are the envelopes of the curve, showing clearly the rapid decrease of the intensity after the beginning of the oscillation. Obviously the apparatus thus far described fully produces the touch noise, and the tones have the character of a piano tone, the intensity of which drops relatively quickly.

The pole piece 19 has preferably a length at least equal to the greater axis of the ellipse E. For the production of a tone in which the touch noise is absent, and the intensity of which does not initially rapidly decrease but may even initially increase gradually, a similar magnet but with its pole piece arranged parallel to the plane A—B may be provided. Thus there will be seen in Fig. 1 magnet 16 with pole piece 17 so arranged, and carrying coil 20. The initial oscillations of the string will not induce a current in the winding 20, since the plane of these oscillations is parallel to the pole piece 17. A current will be induced only after the oscillations have changed

over to the elliptical form. The current will now gradually rise from zero to a maximum value and then decrease slowly. Such a current wave is shown in Fig. 3 of the drawing, a figure corresponding to Fig. 2 described above. From Fig. 5 it appears that the current, and hence sound, intensity indicated by the envelopes *a* increases from zero to a maximum value and then decreases slowly.

10 In Fig. 1 the coils 21 and 20 are connected in series and to the input terminals 4 of the electron tube 5. 21' and 20' are adjustable high ohmic resistances connected in parallel to the coils 21 and 20, respectively. By adjusting these resistances in a suitable manner the ratio of the effects produced by the components of the string oscillations respectively parallel and normal to the plane A—B can be changed in any desired manner, for instance so as to eliminate the touch 15 noise or not. Obviously a net current wave may be obtained of any form between the extremes represented respectively by Figs. 2 and 3.

Any particular intermediate form of current wave may be obtained by employing a single 20 magnet with pole piece suitably inclined to the plane A—B in which the string oscillates directly after the stroke of the hammer. This arrangement has been shown in Fig. 4, wherein further a use of my invention as applied to a piano is 25 diagrammatically shown. In instruments of this type the touch noise does not show particularly in the bass, but is very sharp and troublesome in the treble. Therefore in the bass the pole pieces of the magnets are preferably arranged 30 with little or no inclination relative to the string, so that even the initial oscillation of the string is reproduced, inasmuch as otherwise the bass notes would lose much of their intensity. For the mid notes the magnets are preferably arranged 35 with gradually inclined pole pieces. The magnets of the treble are arranged on one side of the plane of initial oscillation—to wit, the plane determined by the string and hammer. This progressive arrangement is shown in the figure, 40 wherein each magnet is designated as 2, with pole piece 10 and winding 3. Each winding is shown connected to amplifier input terminals 4, which may or may not be common to the several windings, as desired.

50 With the arrangement shown in Fig. 4 the treble notes are produced in a considerably softer manner than in pianos of the well-known type in which the sounds are produced by means of a sound board. The relative intensity of the bass and treble notes is changed so that bass notes 55 comes forth with relatively greater intensity than the treble notes. I have found that many music pieces when played on an instrument as shown in Fig. 4 would give a far better impression.

60 In the embodiments of my invention hitherto described the mechanical oscillator influences an electric circuit by way of electromagnetic induction—i. e., the oscillations are translated from a mechanical into an electrical form by a translating device operating upon an electromagnetic principle. Alternatively electrostatic induction 65 may be employed—i. e., the mechanico-electric translation may be effected by a device operating upon an electrostatic principle. Thus in Fig. 70 5 the string 1 is electrically connected to the input terminal 4 of the grid 1 of the thermionic discharge tube 5. A metal plate 24 connected to the cathode 6 through a battery 25 is arranged adjacent to the string 1. 26 is a resistance inserted between the cathode 6 and the grid 1. The

capacity of the condenser formed by the metal plate 24 and the string 1 is charged to the potential of battery 25, but resistance 26 prevents rapid change of this charge. The capacity is periodically changed when the string oscillates and by virtue of the relative constancy of its charge an alternating voltage is electrostatically induced across it and appears in the input circuit of the tube 5, is amplified by the latter, and is translated into sound by the loudspeaker 9.

10 The effects obtained by various positionings or arrangements, with respect to the string, of the surface of plate 24 nearest the string are the same as discussed for the pole pieces of the magnets in connection with Figs. 1 and 4. By way of example I have illustrated the surface of plate 24 in Fig. 5 as inclined to the plane A—B of initial oscillation of the string. As illustrated this plane is a vertical one, the hammer 1*h* moving in such plane to strike the string.

20 As mentioned above the position of the ellipse E is not necessarily a fixed one, but this ellipse may rotate during the oscillation of the string. The reason for this is that the ends of the string are not tightly fixed but merely rest on a bridge 25 or chevalet. The rotation of the ellipse would result in variations of the reproduced sound which are perceived as beats of the reproduced tone. It is therefore highly desirable to suppress the rotation of the ellipse or at least to eliminate 30 its influence on the current induced in the translating device.

35 In order to accomplish that I provide means for tightly holding the ends of the string. These I have shown in Fig. 5, but it will be understood that this is by way of convenience in illustration only, as the usefulness of the same is obviously generic to all embodiments of my invention. In this figure, for instance, the front end of string 1 is held in semi-circular recesses of 40 blocks 11 and 12. Instead of thus clamping the string end, however, the string may merely be held in a single U- or V-shaped recess, which latter arrangement has been illustrated by the slotted or indentured member 12' at the rear end 45 of the string in Fig. 5. I have found that this holding of the ends of the string prevents rotation of the ellipse E.

50 It will be understood that while I have illustrated and described my invention in terms of specific embodiments thereof, I do not intend any limitation thereby, the scope of my invention being rather to be determined in accordance with the following claims.

55 I claim:

1. In a musical instrument, the combination of a mechanical oscillator; exciting means therefor operable to produce oscillation thereof which comprises initially a component in a single plane only and thereafter components in said plane and in a plane normal thereto; and mechanico-electric translating apparatus having a plurality of surface portions in spaced relationship to said oscillator to be inductively influenced thereby, said portions lying in a plane which is inclined 65 to each of said first mentioned planes.

2. In a musical instrument, the combination of a tuned string and exciting means therefor for producing vibration thereof, said vibration comprising initially a component in a given plane only 70 and thereafter components in said given plane and in a plane normal thereto; and mechanico-electric translating apparatus having a plurality of surface portions in spaced relationship to said string to be inductively influenced thereby, said 75

- portions lying in a plane which is inclined to each of said first mentioned planes.
3. In a musical instrument, the combination of a tuned string and exciting means therefor for producing vibration of each point thereon, said vibration of each point initially comprising oscillation in a straight line and thereafter oscillation in an ellipse; and mechanico-electric translating apparatus having a plurality of surface portions in spaced relationship to a point on said string to be inductively influenced thereby, said portions lying in a line which intersects but is inclined to said first mentioned line.
4. In a musical instrument, the combination of a tuned string and exciting means therefor for producing vibration of each point thereon, said vibration of each point initially comprising oscillation in a straight line and thereafter oscillation in an ellipse; mechanico-electric translating apparatus having a plurality of surface portions in spaced relationship to a point on said string to be inductively influenced thereby, said portions lying in a line which intersects but is inclined to said first mentioned line; and means connected with and influencing the extremities of said string for maintaining substantially fixed the axes of said ellipse of oscillation of said point.
5. In a musical instrument, the combination of a tuned string; exciting means therefor adapted to produce initial oscillation thereof in a given plane; and mechanico-electric translating apparatus having surface in spaced relation to said string and inclined to said plane, said apparatus being inductively influenced by oscillatory variation of the spacing between said string and said surface.
6. In a musical instrument, the combination of a tuned string; exciting means therefor adapted to produce initial oscillation thereof in a given plane; a conductive member having a surface in spaced relation to said string and inclined to said plane, said surface forming an electrical capacity with said string; and means for maintaining a relatively constant charge in said capacity.
7. In a musical instrument, the combination of a tuned string; exciting means therefor adapted to produce initial oscillation thereof in a given plane; a condenser plate arranged adjacent said string and inclined to said plane; and an electric circuit connected to said string and said condenser plate.
8. In a musical instrument, the combination of a tuned string; exciting means therefor adapted to produce initial oscillation thereof in a given plane; a magnet; a winding carried by said magnet; and a pole piece forming part of said magnet and inclined to said plane.
9. A piano comprising bass strings, mid strings and treble strings; hammers adapted to strike said strings and to produce initial oscillation of each in a given plane; and mechanico-electric translating apparatus having portions in spaced relation to, and arranged to be inductively influenced by, said strings, said portions associated with said bass strings being arranged substantially normal to said planes of initial oscillation of said bass strings, said portions associated with said mid strings being inclined to said initial oscillation planes of said mid strings, and said portions associated with said treble strings being arranged substantially parallel to said initial oscillation planes of said treble strings.
10. A piano comprising bass strings, mid strings and treble strings; hammers adapted to strike said strings and to produce initial oscillation of each in a given plane; magnets respectively associated with said strings; windings carried by said magnets; and pole pieces forming part of said magnets respectively and respectively adjacent said strings, said pole pieces associated with said bass strings being arranged substantially normal to said planes of initial oscillation of said bass strings, said pole pieces associated with said mid strings being inclined to said initial oscillation planes of said mid strings, and said pole pieces associated with said treble strings being arranged substantially parallel to said initial oscillation planes of said treble strings.
11. In a musical instrument, the combination of a tuned string; and a mechanico-electric translating system having two portions each arranged to be inductively influenced by said string, said portions being arranged normally to each other and in spaced relation to said string.
12. In a musical instrument, the combination of a tuned string; a mechanico-electric translating system having two portions each arranged to be inductively influenced by said string, said portions being arranged normally to each other and in spaced relation to said string; and selectively operable means for controlling the translations effected by said two portions respectively.
13. In a musical instrument, the combination of a tuned string; two magnets; windings carried by said magnets; and two pole pieces forming part of said magnets respectively, said pole pieces being arranged normally to each other and adjacent to said string.
14. In a musical instrument, a tuned vibrator; exciting means for producing vibration thereof; a pair of translating means for translating from said vibration respectively a series of oscillations having amplitude-time characteristics substantially corresponding to those of said vibration and a series of oscillations having amplitude-time characteristics substantially modified therefrom; and selective means associated with said translating means for controlling the relative amplitudes of the oscillations of said two series.

OSKAR VIERLING.
